Primary Examiner — Antoine D Davis

(57) **CLAIM**

I claim the ornamental design for a tissue level indicator, as shown and described.

DESCRIPTION

FIG. 1 is a front peripheral view of the tissue level indicator; and

FIG. 2 is a top view of the tissue level indicator; and

FIG. 3 is a side view of the tissue level indicator; and

FIG. 4 is a front peripheral view of the tissue level indicator containing a tissue box; and

FIG. 5 is a top view of the tissue level indicator containing a tissue box; and,

FIG. 6 is a side view of the tissue level indicator containing a tissue box.
